[57] CLAIM

The ornamental design for an electrical plug assembly, as shown and described.

DESCRIPTION

FIG. 1 is a top plan view showing my new design for an electrical plug assembly;

FIG. 2 is a right side elevational view thereof;

FIG. 3 is a front elevational view thereof;

FIG. 4 is a bottom plan view thereof;

FIG. 5 is a rear elevational view thereof; and,

FIG. 6 is a rear top right side perspective view thereof. The side opposite to that shown in FIG. 2 is the mirror image thereof.

FIG. 1

FIG. 2

FIG. 3

FIG. 4

FIG. 5

FIG. 6
